DESIGN FOR A CONTAINER FOR ICE CREAM
OR CANDY

Otto Peist, Brooklyn, N. Y.

Application May 14, 1947, Serial No. 139,026

Term of patent 14 years

(Cl. D58—13)

To all whom it may concern:

Be it known that I, Otto Peist, a citizen of the United States of America, residing at 310 Powers Street, Brooklyn, in the county of Kings and State of New York, have invented a new, original, and ornamental Design for a Container for Ice Cream or Candy, of which the following is a specification, reference being had to the accompanying drawing, forming part thereof.

In the drawing

Fig. 1 is a front elevational view of a container for ice cream or candy, showing my new design;

Fig. 2 is an end view thereof as seen from the left hand side of Fig. 1, and

Fig. 3 is a top plan view thereof.

I claim:

The ornamental design for a container for ice cream or candy, as shown.

OTTO PEIST.
